UNITED STATES PATENT OFFICE.

JOSEPH F. KITCHELL, OF NEWARK, NEW JERSEY, ASSIGNOR TO THE R. NEUMANN HARDWARE CO., A CORPORATION OF NEW JERSEY.

BAG-FRAME.

No. 884,593.

Specification of Letters Patent. Patented April 14, 1908.

Application filed March 5, 1907. Serial No. 360,784.

To all whom it may concern:

Be it known that I, JOSEPH F. KITCHELL, a citizen of the United States, residing at Newark, in the county of Essex and State of New Jersey, have invented certain new and useful Improvements in Bag-Frames; and I do hereby declare the following to be a full, clear, and exact description of the invention, such as will enable others skilled in the art to 5 which it appertains to make and use the same, reference being had to the accompanying drawings, and to characters of reference marked thereon, which form a part of this specification.

15 This invention relates, generally, to improvements in the construction of the frames for traveling bags, satchels, and the like; and, the invention has reference, more particularly, to a novel construction of bag- 20 frame for use more especially, with what is known in the art as English or "sewed-in" bags, but which may be used also with any of the other constructions of bag-frames.

In the construction of "sewed-in" bags, 25 that is in that class of bag-frames in which the frame-sections are covered with leather and as at present constructed, when the two hinged frame-sections are closed, there will be more or less of a wide gap formed between 30 a portion of the inner surface of the outer frame-section and a portion of the outer surface of the inner frame-section, on account of the space required in which the leather coverings of the frame-sections are to accommodate 35 themselves.

The present invention, therefore, has for its principal object to provide a novel and simply constructed bag-frame, in which the frame-sections are made in such a manner 40 that the hereinabove stated objections are clearly overcome; and, a further object of this invention is to provide an English or "sewed-in" bag-frame in which the leather-covered frame-sections when in their closed 45 relation will provide a neat arrangement of the parts at the joint; and, when the frame-sections are closed, entirely doing away with any visible gap or space between the closed frame-sections, and providing a frame which, 50 when viewed from either side of the closed frame-sections will have the same appearance.

A further object of this invention is to provide a bag-frame of the English or "sewed-in" type or of the usual sheet-iron or inlay-

frame, in which the frame-sections are L-shaped in cross-section, which can be readily constructed and will have an improved appearance by reason of the fact that one of the frame-sections is provided with a means or device which hides the gap or space formed at the closed frame-sections, and a frame is provided to the frame-sections of which a leather covering is readily applied so as to provide a continuous and even surface, which is more beautiful and artistic in effect and hence greatly enhances the beauty and value of the finished bag.

Other objects of this invention, not at this time more particularly mentioned will be clearly understood from the following detailed description of the same.

With the various objects of my present invention in view, the said invention consists, primarily, in the novel bag-frame hereinafter set forth; and furthermore, this invention consists in the various arrangements and constructions of parts, as well as in the details of the construction of the same, all of which will be more fully set forth in the following specification and then finally embodied in the clauses of the claims which are appended thereto and which form an essential part of this specification.

The invention is clearly illustrated in the accompanying drawings, in which:—

Figure 1 is a front elevation of an English or "sewed-in" bag provided with a leather-covered frame made according to the principles of the present invention; and Fig. 2 is a detail transverse sectional representation of the leather covered frame, made on an enlarged scale, embodying the principles of this invention, and a sectional representation of a part of the upper portion or mouth of the body of the bag, said view illustrating one manner of sewing the bag-body to the frame-sections. Fig. 3 is a front view of the bag-frame embodying the principles of this invention, the frame being shown without its leather coverings; Fig. 4 is an end view of the frame; and Fig. 5 is a similar view of the frame, illustrating the frame-sections in their partly opened relations. Fig. 6 is a transverse section of the bag-frame taken on line 6—6 in said Fig. 3, looking in the direction of the arrow x; Fig. 7 is a similar section taken on line 7—7 in said Fig. 3; and Fig. 8 is a transverse section taken on line 8—8 in the same figure; all of said sections being made

on an enlarged scale. Fig. 9 is a front elevation of a sheet-iron or inlay-frame, provided with a means for hiding the gap or space between the closed frame-sections, said means embodying the principles of the present invention; and Fig. 10 is a transverse sectional representation of said frame, said section being made on an enlarged scale and being taken on line 10—10 in said Fig. 9. Fig. 11 is an elevation of a sheet-metal frame provided with a gap or space-hiding means or device of a slightly modified form of construction; and Fig. 12 is a transverse vertical section of the said frame, said section being taken on line 12—12 in Fig. 11 and being made on an enlarged scale.

Similar characters of reference are employed in all of the above described views to indicate the corresponding parts.

Referring now to the several figures of the drawings, the reference-character 1 indicates an English or "sewed-in" bag, the respective leather-body-portions 2 and 3 being secured to the respective frame-sections of the bag-frame by means of stitches 4. The said bag-frame consists of an outer frame-section and an inner frame-section which are provided with the usual downwardly extending leg-portions which are hinged or pivoted in any suitable manner at their lower ends, as will presently appear.

Referring now more particularly to Figs. 2 to 8 inclusive, it will be seen that the outer frame-section consists, essentially, of a main frame or body-section 5, formed at its ends with downwardly extending leg-portions or members 6; and the said inner frame-section consists, essentially, of a main frame or body-section 7, also formed at its ends with downwardly extending leg-portions or members 8, the said leg-portions 6 and 8 being provided with a suitable means of pivotal connection 9, as will be clearly evident from an inspection of Fig. 3 of the drawings. Any suitably constructed means of pivotal connection may be employed to connect the two frame-sections in a hinge-like manner. To the said frame-section 5, and its leg-portion 6 are secured at convenient intervals, by means of pins, or rivets 10, suitably constructed arms 11 which are formed with the angularly bent portions 12, so as to provide brackets upon which is supported and secured by means of pins or rivets 13 an outer frame-plate 14, said plate being bent at its respective ends to provide the downwardly extending end-portions or members 15. The brackets connect the said outer plate 14 and its downwardly extending members 15 to the said frame or body-section 5 in such a manner that an open space 16 will be provided substantially as shown. Suitably secured at convenient intervals to the said frame-sections 7 and its leg-portions 8, by means of pins or rivets 17, are suitably con-

structed arms 18 which are formed with angularly bent portions 19, so as to provide brackets, upon which is supported and secured by means of pins or rivets 20, or in any other suitable manner, one form of the gap or space-hiding means or device made according to the principles of the present invention. This means or device is indicated by the reference-character 21, and the same comprises a main body-portion 22 which is formed at its ends with downwardly extending members or elements 23.

In cross-section, the main body and the downwardly extending members or elements of this gap or space-hiding or closing device, are made substantially L-shaped in cross-section, as clearly illustrated in Figs. 2, 6, 7 and 8 of the drawings, and when the inwardly extending parts of this device 21 have thus been secured upon the said angularly bent portions 19 of the arms 18, said device 21 will be located sufficiently above the outer marginal edges of the frame or body-section 7 and its leg-portions 8 to provide a surrounding space 25, as clearly illustrated. These parts are arranged in their assembled relation in such a manner, that the outer marginal edges 27 of the main body-portion 22 and its downwardly extending members or elements 23 will lie in the plane of the outer faces 26 of the outer frame-section or plate 14, and its downwardly extending portions or members 15, substantially as illustrated in said Figs. 6, 7 and 8 of the drawings, whereby, when the two frame-sections are brought into their closed relations, the intervening space or gap 24, usual in the frame constructions of to-day, is completely hidden from view. The two frame-sections, as will be seen from an inspection of Fig. 2 of the drawings, are usually and suitably incased in leather or other suitable coverings 28 and 29, the coverings being arranged and secured about the said frame-sections in any well-known manner, and the edge 30 of the covering 29, owing to the arrangement of the gap-closing or hiding device, lying in the planes of the outer faces 31 of the covering which surrounds the other frame-sections, all of which is clearly illustrated in said Fig. 2 of the drawings, and whereby, when the said frame-sections and their coverings are secured to the bag-portions 2 and 3 by means of the stitches 4, a complete and beautifully finished bag will be the result which is minus the usually exposed and objectionable space or gap formed between the closed frame-sections, and a bag will be the result which when viewed from either side will have the same general appearance. A space or gap closing or hiding means or device may also be used with the ordinary sheet-iron or inlay-frame of the usual L-shaped cross-section, as clearly indicated in Figs. 9 to 12 inclusive. In the said figures, the reference-characters

32 and 33 indicate the usual pivotally connected or hinged frame-sections, and 34 and 35 are the respective L-shaped members or portions of said frame-sections, which are pivoted in such a manner, that a space 36 is produced between a portion of the inner face of the member 34 and the outer face of the member 35.

Referring now to Figs. 9 and 10, it will be seen that the said frame-section 35 has arranged upon the outer face of its L-shaped member 35 an L-shaped gap or space closing or hiding device 37 which is secured in place by means of pins or rivets 38 and is of the general construction and configuration of the L-shaped space of gap-closing or hiding device 21, which was fully described in the foregoing specification and illustrated in Figs. 1 to 8 inclusive. In lieu of either of the said L-shaped space or gap closing or hiding devices 27 or 37 hereinabove described, a modified form of construction of space or gap-closing or hiding device 29 may be used in the manner indicated in Figs. 11 and 12 of the drawings. As shown, this device 39 is made from flat sheet metal and is of the general outer conformation of the frame-section 33, said device 39 being secured to the outer face of the L-shaped portion of the frame-section 33 by means of pins or rivets 40, and having its outer marginal edge-portions terminating in the plane of the outer faces of the member 34 of the frame-section 32, as clearly illustrated in said Figs. 11 and 12.

From the foregoing description of my present invention, it will be clearly evident that I have produced a bag-frame in which the objectionable space or gap between the respective frame-section is completely hidden from view, and have provided a frame which is easily made and does not add to the general expense of manufacture, and when finished and used in connection with a bag, provides a bag of much neater appearance than the bag provided with the frames of the present constructions.

I claim:

1. A bag-frame comprising a pair of frame-sections, each frame-section having leg-portions, and one of said frame-sections being adapted to move into the other frame-section, so as to be inclosed by the latter, a means of pivotal connection between each pair of leg-portions of the frame-sections, and means upon the smaller frame-section constructed and arranged to extend over a portion of the larger frame-section so as to cover or hide the space or gap between the two frame-sections when closed.

2. A bag-frame comprising a pair of frame-sections, each frame-section having leg-portions; and one of said frame-sections being adapted to move into the other frame-section so as to be inclosed by the latter, a means of pivotal connection between each

pair of leg-portions of the frame-sections, and an L-shaped space or gap-hiding means upon the smaller frame-section, the upwardly extending leg of said L-shaped space or gap-hiding means extending over a portion of the larger frame-section so as to cover or hide the space or gap between the two frame-sections when closed.

3. A bag-frame comprising a pair of pivotally connected frame-sections, one of said frame-sections being provided with a forwardly extending body-portion and downwardly extending leg-portions, the other frame-section being provided with an inwardly extending body-portion and downwardly extending leg-portions the frame-section with the inwardly extending portions being made smaller than the frame-section with the outwardly extending portions, so that the smaller frame-section will move into the larger frame section, and a space or gap-hiding means on said smaller frame-section, and arranged to extend over a portion of the larger frame-section so as to cover or hide the space or gap between the two frame-sections when closed, substantially as and for the purposes set forth.

4. A bag-frame comprising a pair of pivotally connected frame-sections, one of said frame-sections being provided with forwardly extending body-portion and downwardly extending leg-portions, the other frame-section being provided with an inwardly extending body-portion and downwardly extending leg-portions, the frame-section with the inwardly extending portions being made smaller than the frame-section with the outwardly extending portions, so that the smaller frame-section will move into the larger frame section, and an L-shaped space or gap-hiding means mounted and secured upon the faces of the inwardly extending body-portions and leg-portions of said smaller frame-section, and arranged to extend over a portion of the larger frame-section so as to cover or hide the space or gap between the two frame-sections when closed, substantially as and for the purposes set forth.

5. A bag-frame comprising an outer and an inner frame-section, each frame-section comprising a main body and leg-portions at its ends, all arranged that the inner frame-section may be inclosed by the outer frame-section, and a space or gap-hiding device mounted upon the body and leg-portions of the inner frame-section, said device having upwardly and outwardly extending portions corresponding to and terminating at the marginal edge-portions of the main body and leg-portions of the outer frame-section to hide the space or gap between the closed frame-sections, substantially as and for the purposes set forth.

6. A bag-frame comprising an outer and an inner frame-section, each frame-section

comprising a main body and leg-portions at its ends, all arranged that the inner frame-section may be inclosed by the outer frame-section, and an L-shaped space or gap-hiding device mounted upon the upper and outer faces of the body and leg-portions of the inner frame-section, said device having upwardly and outwardly extending portions corresponding to and terminating at the marginal edge-portions of the main body and leg-portions of the outer frame-section to hide the space or gap between the closed frame-sections, substantially as and for the purposes set forth.

15 7. A bag-frame comprising a pair of frame-sections, brackets on each frame-section, an outer frame-plate mounted upon the brackets of one of said frame-sections to provide a sewing space between said plate and the frame-section, and a space or gap-hiding device mounted upon the brackets of the other frame-section to provide a sewing space and said device being arranged to close or hide the space or gap between the closed frame-sections, substantially as and for the purposes set forth.

8. A bag-frame comprising a pair of frame-sections, brackets on each frame-section, an outer frame-plate mounted upon the brackets of one of said frame-sections to provide a sewing space between said plate and the frame-section, and an L-shaped space or gap-hiding device mounted upon the brackets of the other frame-section to provide a sewing space and said gap-hiding device having upwardly and outwardly extending portions which correspond to and terminate at the marginal edge-portions of the outer frame-plate to hide the space or gap between the closed frame-sections, substantially as and for the purposes set forth.

9. The herein described bag-frame comprising a frame-section 5 having leg-portions 6, brackets secured to said frame-section and said leg-portions, and a frame-plate mounted upon said brackets, said plate having downwardly extending end-members, a second frame-section 7 having leg-portions 8, brackets secured to said frame-section and said leg-portions, and a space or gap-hiding device mounted upon the brackets of said frame-section 7 and the leg-portions 8, substantially as and for the purposes set forth.

10. The herein described bag-frame comprising a frame-section 5 having leg-portions 6, brackets secured to said frame-section and said leg-portions, and a frame-plate mounted upon said brackets, said plate having downwardly extending end-members, a second frame-section 7 having leg-portions 8, arms 18 secured to said frame-section 7 and the

leg-portions 8, each arm having an angularly bent portion, and an L-shaped space or gap-hiding device mounted upon said angularly bent portions of said arms 18, said space or gap-hiding device having upwardly and outwardly extending portions which correspond to and terminate at the marginal edge-portions of said frame-plate and its downwardly extending end-members, substantially as and for the purposes set forth.

11. A bag-frame comprising a pair of frame-sections, one of said frame-sections being adapted to move into the other frame-section so as to be inclosed by said latter frame-section, but the inclosed frame-section being constructed with a part which is flush with the outer surface-portions of the inclosing frame-section, so that there shall be no exposed gap or space between the two closed frame-sections, substantially as and for the purposes set forth.

12. A bag-frame comprising a pair of frame-sections, each frame-section having leg-portions, and one of said frame-sections being adapted to move into the other frame-section, a means of pivotal connection between each pair of frame-sections, and an L-shaped space or gap-closing device, said device corresponding to the general shape of the smaller frame-section and surrounding the latter, and said closing device being arranged in the open space or gap of the closed frame-sections and having a portion extending from said gap over a portion of the larger frame-section so as to close said gap, substantially as and for the purposes set forth.

13. A bag-frame comprising a pair of frame-sections, each frame-section having leg-portions, and one of said frame-sections being adapted to move into the other frame-section, a means of pivotal connection between each pair of frame-sections, and an L-shaped space or gap-closing device, said device corresponding to the general shape of the smaller frame-section and surrounding the latter, and said closing device being arranged in the open space or gap of the closed frame-sections and having a portion extending from said gap over a portion of the larger frame-section so as to close said gap, and angularly bent arms secured to said smaller frame-sections forming brackets for the support thereon of the gap-closing device, substantially as and for the purposes set forth.

In testimony, that I claim the invention set forth above I have hereunto set my hand this first day of March, 1907.

JOSEPH F. KITCHELL.
